UNITED STATES PATENT OFFICE.

HARRY J. PARKER, OF SAN FRANCISCO, CALIFORNIA, ASSIGNOR, BY DIRECT AND MESNE ASSIGNMENTS, TO SIDNEY WILLIAMS, OF SAN FRANCISCO, CALIFORNIA,

AEROPLANE.

1,337,151.

Specification of Letters Patent.

Patented Apr. 13, 1920.

Application filed July 17, 1917. Serial No. 181,022.

To all whom it may concern:

Be it known that I, HARRY J. PARKER, a citizen of the United States, residing at the city and county of San Francisco and State 5 of California, have invented certain new and useful Improvements in Aeroplanes, of which the following is a specification.

This invention relates to an improvement in aeroplanes, and one of the objects is to 10 arrange the planes or wings in such a manner as to present at all times the maximum amount of plane surface to prevent the fall of the machine.

Another object of my invention is to 15 mount the planes upon the frame in such a manner that the frame will, at all times, maintain substantially a vertical position.

A further object of my invention is to construct the rudder in such a manner as to 20 completely control the guiding of the machine in all directions by one steering-handle.

In the accompanying drawings:—

Figure 1 is a side elevation of the device; 25 Fig. 2 is a front elevation thereof;

Fig. 3 is an enlarged longitudinal section of the frame and plane mounting, taken on line 3—3 of Fig 2;

Figs. 4 and 5 are longitudinal sections 30 through the rudder portion taken at right-angles to each other;

Fig. 6 is an enlarged detail view of the steering-mechanism;

Fig. 7 is a detail view of the frame bearing;

Fig. 8 is an enlarged plan view of one of the planes or wings.

A, represents a substantially rectangular frame, consisting of upright members 1 and 2, and horizontal members 3 and 4. 5, 5, indicate the usual ground wheels attached to the lower front and rear portion of the frame. Extending longitudinally of the upper member 4, 4, of the frame is a cylindrical frame B, fixed against rotation with respect to the main frame, and consists of a plurality of annular bands 6, 7, 8 and 9, the outer bands 6 and 9 being preferably provided with outwardly-extending flanges 45 10 and 11, said plurality of bands being connected together by longitudinal strips 12.

Mounted in the forward end of the frame, and below the center thereof, is a drive motor 13, to which a propeller 14 is suitably con-

nected. 15 indicates a fuel tank arranged at 55 the rear, and above the center of the cylindrical frame.

12' indicates a rotating tubular frame provided at its ends with upwardly-extending flanges. Extending radially from the cylindrical frame B are a plurality of equally spaced planes or wings 17, secured thereto by suitable lugs 18. These planes are braced at their outer ends by suitable wires 19, 19, running circumferentially thereof. These 65 planes or wings, as disclosed in Fig. 8, preferably consist of an outer frame, shaped as disclosed, having arranged longitudinally thereof a plurality of ribs 20, which are covered by suitable material 21. 70

Numeral 22 indicates the pilot-seat arranged at the lower forward end of the frame, and directly below the propeller.

It will thus be seen that the tubular frame and planes or wings are free to rotate with 75 respect to the main frame, thereby presenting at all times a maximum amount of plane surface for supporting the weight of the machine. Furthermore, with this construction, the operator's seat always remains in a 80 substantially vertical position, owing to the fact that the frame, engine, and operator's seat are well below the center of the planes.

As noted in Fig. 1, the longitudinal strips 12 are adapted to extend rearwardly of the cylindrical bands and support a rudder C. This rudder consists preferably of a hollow tube 23, having arranged radially thereof a plurality of fins 24, 24, which likewise are braced at their outer ends by suitable wires 90 25 running circumferentially thereof. Centrally arranged within the tube 23 is a band 26, to which is pivotally connected a pair of supporting members 27, 27, which extend outwardly from the tube, the free ends thereof being bent at right-angles to the body portion which is secured to a block 29, pivotally connected on a vertical axis 30, at 95 right-angles to the pivotal support of the tube portion of the rudder, to the rear end 100 end of the rearwardly-extending strips 12, 12, by suitable trunnion-plates 31. Brace 32 extending downwardly from the supporting strips 12, 12, is adapted to further stiffen the frame structure. 105

As will be seen, this mounting affords a universal movement of the rudder, and by means of a single steering lever 33, which

is preferably constructed in the following manner:—

Extending below the operator's seat 22 (as shown in Fig. 6) is a frame 34, which is 5 adapted to support the steering-handle socket 35. Arms 36, projecting outwardly from the frame, support suitable pulleys 37. Arranged directly above these arms are a 10 plurality of cross-arms 38, 38, and 39, 39, extending at right-angles from the main steering lever 33. At the outer ends of these arms are connected a plurality of guide wires 40 and 41, which preferably lead to a vertically-disposed bar 42 mounted at the 15 forward end of the tube 23, as clearly shown in Fig. 4.

Thus it will be seen that, as the steering-handle 33 is moved longitudinally or backward and forward of the machine, the 20 rudder will be moved vertically about the axis arranged centrally of the tube, thereby causing the machine to travel in an upward or downward direction, while the transverse cross-arms 39, 39, are connected to similar 25 guide wires 43 and 44, which are in turn connected to the outer end of the transverse members 28, thereby making it possible to cause a lateral movement of the rudder by the lateral movement of the steering-handle 33, which in turn will cause the machine 30 to travel in a transverse direction, as desired. It will be seen that this arrangement of steering greatly simplifies the manipulation 35 of a machine, inasmuch as the handle is moved in exactly the direction in which it is desired to have the machine travel.

I claim:—

1. In an aerial apparatus, the combination 40 with a hollow main frame, the body portion of which is provided with flanged members, a portion of said main frame extending rearwardly of the body portion and provided with a universally movable rudder, of a substantially rectangular frame suspended 45 from the body portion of the main frame, a cylinder rotatably journaled on said body portion between the flanged members and provided with a plurality of radially-projecting planes, and means carried 50 upon said rectangular frame for actuating the universally movable rudder.

2. In an aerial apparatus, the combination 55 of a skeleton frame the body portion of which consists of a plurality of annular bands secured together by a plurality of longitudinal strips, the outermost annular bands being flanged, said longitudinal strips adapted to extend rearwardly of said body portion, a substantially rectangular frame suspended 60 from the body portion of said skeleton frame, a tubular frame provided with a plurality of radially-projecting planes rotatably mounted upon said body portion and held thereon by said flanged bands, propelling means mounted upon said skeleton frame and within said tubular frame, a universally movable rudder mounted rearwardly of said skeleton frame, and actuating means for said rudder carried by the lower portion of said rectangular frame.

portion and held thereon by said flanged bands, propelling means mounted upon said skeleton frame and within said tubular frame, a universally movable rudder mounted rearwardly of said skeleton frame, and actuating means for said rudder carried by the lower portion of said rectangular frame.

3. In an aerial apparatus, the combination of a main frame, the body portion of which is composed of a plurality of annular bands connected together by a plurality of longitudinally extending strips, the outer free ends of which are adapted to be brought together, a universally movable rudder pivotally mounted on the outer ends thereof, a substantially rectangular frame suspended 80 from the body portion of said main frame, a tubular portion rotatably mounted upon said body portion, and provided with a plurality of radially-arranged planes, propelling means arranged within the body portion of said main frame, a propeller extending 85 forwardly of the radially-arranged planes, and means carried upon the rectangular frame for actuating said rudder.

4. In an aerial apparatus, the combination 90 with a hollow main frame, the body portion of which is provided with annular flanged members, said main frame extending rearwardly of the body portion and provided with a universally movable rudder 95 consisting of a drum having a plurality of fins projecting radially therefrom, of a substantially rectangular frame suspended from the body portion of the main frame, a cylinder rotatably journaled on the said body 100 portion between the flanged members and provided with a plurality of radially-projecting planes, and means carried on said rectangular frame for actuating the universally movable rudder.

5. In an aerial apparatus, the combination 105 with a skeleton frame, which consists of a plurality of annular bands secured together by a plurality of longitudinal strips, the outermost annular bands being flanged, said longitudinal strips being adapted to extend rearwardly of said body portion, of a substantially rectangular frame suspended from the body portion of said skeleton frame, a tubular frame provided with a plurality of radially-projecting planes rotatably mounted upon said body portion and held therein by said flanged bands, a universally movable rudder consisting of a drum having a plurality of fins projecting radially therefrom, 110 means carried upon said rectangular frame for actuating the rudder, and propelling means mounted within said skeleton frame.

In testimony whereof I affix my signature.

HARRY J. PARKER.
